US00D831139S

(12) United States Design Patent (10) Patent No.: US D831,139 S
(45) Date of Patent: * Oct. 16, 2018

(54) SOCER BALL

(71) Applicant: Matthew John O'Malley, San Diego, CA (US)

(72) Inventor: Matthew John O'Malley, San Diego, CA (US)

() Term: 15 Years

(21) Appl. No.: 29/570,116

(22) Filed: Jul. 5, 2016

Related U.S. Application Data

(60) Continuation-in-part of application No. 29/527,943, filed on May 22, 2015, now abandoned, which is a division of application No. 29/495,499, filed on Jul. 1, 2014, now Pat. No. Des. 735,280.
